CLAIM

The ornamental design for a liquid dispenser, as shown and described.

DESCRIPTION

FIG. 1 is a perspective view of a liquid dispenser in accordance with the present invention;

FIG. 2 is a top plan view of the liquid dispenser illustrated in FIG. 1;

FIG. 3 is a side elevational view of the liquid dispenser illustrated in FIGS. 1 and 2, the opposite side elevational view being a mirror image thereof;

FIG. 4 is a front elevational view of the liquid dispenser illustrated in FIGS. 1-3; and,

FIG. 5 is a rear elevational view of the liquid dispenser illustrated in FIGS. 1-4.
